UNITED STATES PATENT OFFICE.

CLIVE M. ALEXANDER, OF PORT ARTHUR, TEXAS, ASSIGNOR TO GULF REFINING COMPANY, OF PITTSBURGH, PENNSYLVANIA, A CORPORATION OF TEXAS.

PROCESS OF MAKING AROMATIC HYDROCARBONS.

1,230,975.

Specification of Letters Patent. Patented June 26, 1917.

No Drawing.

Application filed November 10, 1915. Serial No. 60,746.

To all whom it may concern:

Be it known that I, CLIVE M. ALEXANDER, a citizen of the United States, residing at Port Arthur, in the county of Jefferson and State of Texas, have invented certain new and useful Improvements in Processes of Making Aromatic Hydrocarbons, of which the following is a specification.

This invention relates to processes of making aromatic hydrocarbons; and it comprises a method of producing the lower boiling aromatic hydrocarbons, such as toluene and benzene (benzol) from the higher-boiling aromatic hydrocarbon materials such as the higher boiling tar oils, and particularly from the commercial grade known as solvent naphtha, wherein such higher boiling oils are transmitted in vapor form through a retort or tube heated to a temperature of from 600 to 1,000° C., but best around 800° C. at a rate sufficiently rapid to give a liquid condensate of around 70 per cent. of the original volume of the oil treated and sufficiently rapid to give a substantial proportion of high-boiling oil going beyond the heated zone while also converting a substantial proportion into lower boiling oils and wherein the condensate is redistilled to recover the low boiling oils formed and residual high-boiling oils, said residual high boiling oils being then retreated in the same manner; all as more fully hereinafter set forth and as claimed.

The main source of aromatic or cyclic hydrocarbons is coal tar or coal gas, produced by the destructive distillation of coal. The commercial demand is largely for the lower boiling oils, benzene (benzol) and toluene while there is much less demand for the higher boiling oils which consequently sell at a much lower price. I have found that I can cheaply and readily convert these higher boiling oils into lower-boiling oils of greater value by a process which in substance consists in breaking up the vapors of such high-boiling oils by heat under carefully regulated conditions.

While the present process is applicable to other aromatic materials of high boiling point, I regard it as particularly useful in the treatment of what is known commercially as solvent naphtha; a neutral coal tar distillate boiling for the most part between 130 and 180° C. I shall therefore herein-after discuss this material more specifically. The present process may however be applied

to a variety of other aromatic, comparatively high boiling products; even phenolic oils. In treating high boiling phenolic oils, the phenols break down into lower boiling phenols, just as the hydrocarbons break down into lower boiling hydrocarbons.

On passing solvent naphtha vapors through a hot tube or retort, the results vary according to conditions; but there is always a breaking down of the contained high boiling hydrocarbons with the production of gas, tarry materials and low boiling hydrocarbons in varying proportions. Since it is the low-boiling hydrocarbons which are desired, production of gas and tarry materials is, for the present purposes, a waste; and conditions must accordingly be provided wherein the production of gas and tarry materials is as small as possible.

As I have found, the ratio of gas and tar to hydrocarbons depends largely upon the temperature and upon the rate of feed; or, in other words, upon the time factor; the time during which the vapors are exposed to the temperature chosen. For example at higher temperatures more rapid rates of oil feed must be used in order to obtain results equivalent to those at lower temperatures. In some ways the use of higher temperatures with increased rates of oil feed is an advantage in that the capacity of a given apparatus is thereby increased. The temperature may range between 600° and 1000° C., but as a general rule I find temperatures around 800° C. best adapted. The best rate of feed will of course depend in a measure upon the particular apparatus used in performing the process; but the best rule, and one which is generally applicable, is to feed the solvent naphtha or its vapors to the reaction zone, which may be in a heated tube or retort of any kind, at such a rate that the effluent gases and vapors on condensing in any ordinary way, as by the use of cooling water etc., will give a liquid condensate of at least 70 per cent. of the volume of the original solvent naphtha.

The condensate should also upon redistillation give about a third of its volume of oils having the same boiling point, or range of boiling points, as the original solvent naphtha. In other words, the solvent naphtha is fed through the reaction zone at such a rate of speed that while a substantial portion of it is converted into low boiling hydrocarbons a substantial

portion of it still remains as high boiling hydrocarbons, say about 30 per cent. of the original volume. With a less rapid rate of feed, the proportion of gas and tar goes up unduly. But as stated, in operating the process much depends upon the particular apparatus used since obviously with a long heated zone the conditions are quite different than with a short heated zone and feed conditions must be correspondingly changed.

Any suitable heating apparatus permitting transit of vapors therethrough may be employed; such as an iron or clay tube or retort having inlet means at one end and outlet means at the other, the outlet means being connected to any suitable condenser. The tube or retort may be vertical or horizontal; but I prefer a vertical retort or tube with a top feed thereby obviating dangers of stratification. Any suitable heating means, such as fire heat, electrical heat, flame heat from burning oil or gas, etc. may be adopted. The waste gas of the operation may be used in heating. This process may be carried out at atmospheric pressure or at a pressure above or below atmospheric pressure. Operation at atmospheric pressure gives very good results.

The solvent naphtha or other high boiling aromatic hydrocarbon may be introduced into the tube or retort as a sprayed liquid or as vapors coming from a pre-heater.

In the typical embodiment of the present process, I vaporize solvent naphtha in any suitable heating apparatus and pass the vapors through a heated zone in which they are heated to a predetermined temperature. The rate of feed for temperatures ranging from 600° to 1000° C. is so adjusted to the particular apparatus in use that on cooling the effluent gases and vapors, a liquid condensate of about 70 per cent. of the volume of the solvent naphtha used is recovered. Such effluent gases and vapors are cooled and the liquid condensate separated from the gas. This gas contains a considerable amount of vapors of benzol and toluol even where the cooling in condensation is to a low degree. The gas may be treated in the well understood ways with "wash oil" (high boiling petroleum distillates) to absorb the benzene and toluene which are subsequently boiled off and recovered. The liquid condensate is distilled in any of the usual types of apparatus. It will ordinarily give 20 to 25 per cent. of material boiling between 75 and 130° C. which may be condensed and redistilled for benzene and toluene in the usual way. It will ordinarily give about 30 per cent. of high boiling oil much like the original oil. This high boiling oil is distilled over and returned to the heating zone alone or with new solvent naphtha. There will be about 20

per cent. of a tarry residue containing naphthalene, diphenyl, etc. These may be recovered and utilized. The high boiling fraction which is re-run, on again heating in the same manner gives a somewhat higher yield of low boiling fractions than before. It will be seen, that in the described operation, I am running solvent naphtha vapors through a heated zone at such a rate that about a third of the liquid remains of the original boiling point and this third is recovered and re-run together with new solvent naphtha.

On treating creosote oils and other mixed coal tar products in the same way somewhat more complicated condensates are obtained; these condensates containing not only low boiling hydrocarbons derived from the high boiling hydrocarbons but also low boiling phenols. These low boiling phenols may be separated from the condensate and the low boiling hydrocarbons therein contained, in any of the usual ways.

What I claim is:

1. The process of converting high boiling aromatic hydrocarbons into low boiling aromatic hydrocarbons which comprises passing the vapors of such high boiling hydrocarbons through a heated zone maintained at a cracking temperature at a rate so rapid as to give a substantial proportion of unchanged high boiling hydrocarbon of the original boiling point passing such zone.

2. The process of converting high boiling aromatic hydrocarbons into low boiling aromatic hydrocarbons which comprises passing vapors of solvent naphtha through a heated zone maintained at a cracking temperature at a temperature of 600° to 1000° C. and at a rate sufficiently rapid to give a condensate having about 70 per cent. the volume of the original solvent naphtha and containing high boiling oils.

3. The process of making benzene and toluene from solvent naphtha which comprises passing the vapors of such solvent naphtha through a zone heated to 600° to 1000° C. at a rate sufficiently rapid to give a large volume of liquid condensate containing high boiling oils, condensing the so treated vapors, separating benzene and toluene therefrom, and recovering high boiling oils.

4. The process of making benzene and toluene from high boiling aromatic oils which comprises passing a mixture of vapors of once run high boiling oil and of fresh high boiling oil through a heated zone at a temperature of 600° to 1000° C., recovering high boiling oils from such condensate and returning the recovered high boiling oils together with a fresh portion of high boiling oil to the heating zone for re-running.

5. The process of converting high boiling

aromatic hydrocarbons into low boiling aromatic hydrocarbons which comprises passing vapors of solvent naphtha through a heated zone at a temperature of about 800°

5 C. and at a rate sufficiently rapid to give a condensate having about 70 per cent. the volume of the original solvent naphtha and containing high boiling oils.

6. The process of making benzene and 10 toluene from solvent naphtha which comprises passing the vapors of such solvent naphtha through a zone heated to about 800° C. at a rate sufficiently rapid to give a large volume of liquid condensate, condensing the so treated vapors, separating benzene and toluene therefrom, and recovering high boiling oils.

7. The process of making benzene and toluene from high boiling aromatic oils 20 which comprises passing a mixture of once run high boiling oil and fresh high boiling oil through a heated zone at a temperature of about 800° C., recovering high boiling

oils from such condensate and returning the recovered high boiling oils together with a 25 fresh portion of high boiling oil to the heating zone for re-running.

8. In the process of making benzene and toluene from solvent naphtha, the process which comprises producing vapors from a 30 mixture of solvent naphtha and once-treated oil, passing such vapors through a heated zone maintained at a cracking temperature at a rate sufficiently rapid to insure a substantial portion of such vapors passing 35 through unchanged, condensing the so treated vapors, separating low boiling constituents from the condensate, recovering high boiling oils therefrom and returning the recovered high boiling oils for admixture with fresh solvent naphtha to produce 40 the described mixture.

In testimony whereof, I affix my signature.

CLIVE M. ALEXANDER.
